Mots Law, PLLC(57) **CLAIM**

The ornamental design for a cleaner and charger unit for electric shaver, as shown and described.

DESCRIPTION

FIG. 1 is a perspective view of front, right side, and top of a cleaner and charger unit for electric shaver;

FIG. 2 is a perspective view of right side, rear and bottom thereof;

FIG. 3 is a front view thereof;

FIG. 4 is a rear view thereof;

FIG. 5 is a right side view thereof;

FIG. 6 is a left side view thereof;

FIG. 7 is a top plan view thereof;

FIG. 8 is a bottom plan view thereof;

FIG. 9 is a sectional view thereof taken along line 9-9 of FIG. 3, in which the internal components are omitted; and,
FIG. 10 is a reference perspective view showing thereof in use.

The portions of the article in broken lines are shown for illustrative purposes only and form no part of the claimed design.
